UNITED STATES PATENT OFFICE.

CONRAD EKVALL, OF ELGIN, ILLINOIS.

MILK-PAIL HOLDER.

1,048,303.

Specification of Letters Patent. Patented Dec. 24, 1912.

Application filed May 1, 1912. Serial No. 694,313.

To all whom it may concern:

Be it known that I, CONRAD EKVALL, a citizen of the United States of America, residing at 272 Commonwealth avenue, in the 5 city of Elgin, in the county of Kane and State of Illinois, have invented certain new and useful Improvements in Milk-Pail Holders, of which the following is a specification, reference being had therein to the accompanying drawing.

This invention relates to animal industry and has special reference to a milk pail for use in dairies.

The principal object of the invention is to 15 provide a pail which can readily be supported upon the knees of the user, the support being of improved construction and arranged so that there is no danger of the same collapsing and permitting the upsetting 20 of the pail.

With the above and other objects in view, the invention consists, in general, of certain novel details in construction and combinations of parts, hereinafter fully described, 25 illustrated in the accompanying official drawings and specifically claimed.

In the accompanying drawings like characters of reference indicate like parts in the several views.

30 Figure 1 is a detail perspective showing the manner of using the pail. Fig. 2 is a side elevation of a pail constructed in accordance with this invention, certain parts being shown in section better to bring out 35 the details. Fig. 3 is an enlarged detail view of a portion of one of the supporting arms showing the manner in which the bail of the pail is used to lock the same in its raised position. Fig. 4 is a side view to 40 reduce the scale taken at right angles to Fig. 2. Fig. 5 is a view showing in full and dotted lines, different positions of the pail. Fig. 6 is a detail perspective of certain ears used herewith. Fig. 7 is a detail 45 perspective of one of the supporting arms. Fig. 8 is a detail perspective of a certain pocket used to prevent rattling of the supporting arms and their swinging from side to side when the pail is being carried by the 50 handle on the bail.

The body of the pail is, preferably, in a general inverted frusto-conical form, as illustrated at 10, and is provided with a pouring lip or spout 11. Attached to the body 55 at oppositely disposed points of its upper edge, are certain lugs which each comprise

a body-portion 12, having a rectangular opening 13 formed therein, at its lower end and a circular opening 14 at its upper end. Below the body-portion 12 there is provided a reduced extremity 15 having suitable rivet-receiving openings 17 through which and the wall of the pail pass rivets 18, which serve to secure the lugs firmly in place. Extending transversely across each of the openings 13 is a bolt 19; thereon is mounted a respective supporting arm. Each of these arms consists of a, preferably, straight body-portion 20 having what may be termed a foot 21 extending substantially 60 at right-angles thereto, the foot being irregularly curved to provide a toe 22 and a heel 23. In the body of the foot there is provided a slot which extends substantially transverse the foot and is indicated at 24. 65 Through the slots 24 pass bolts 19.

The pail is provided with an ordinary wire bail 25 substantially semi-circular in shape and having a gripping handle 26 located thereon, the ends of the wire forming 70 the bail pass through the openings 14 and are arcuately curved as at 27, terminating in eyes 28. These arcuate ends 27 lie in planes substantially at right-angles to the plane of the body of the bail 25 so that they are 75 rocked backward and forward as the handle 26 is raised or depressed.

Adjacent the bottom of the bail directly below the lugs 12, there is provided a pocket consisting of a base-plate 29 whereon is 80 formed a cup 30 adapted for the reception of the lower end of one of the members 20.

In the operation of the device, the parts are, at the beginning of the milking, in the position in Fig. 2. This keeps the handle 95 26 conveniently raised as the arcuate member 27 engages the upper end or foot of the member 20, and is thereby prevented from rotating. The milk man grasps the handle 26 and carries it to the barn or other place 100 where the milking is to be done; he then sets the pail upon the ground and raises each of the members 20 slightly until the lower end thereof swings clear of the respective pocket 30, then by depressing the handle 26 the 105 toes 22 will be caused to move downward and the supports to move upward. He then seats himself upon the milking stool and, grasping the members 20, lifts the pail and places its handles or members on his knees 110 so that the pail swings freely therebetween. It is obvious, of course, he can adjust the

pail, as to angle, by pressure on the sides, as can be seen by reference to Fig. 1. After the milking operation has been completed, he simply lifts the pail off his knees and the members 20, owing to their leverage and weight, cause the bail 25 and handle 26 to rise and reassume the position shown in Fig. 2. It is to be noted that the strain due to the heels and toes of the members 20 is brought upon the lugs 12 and not upon the milking bucket or pail itself.

There has thus been provided a simple and efficient device of the kind described for the purpose specified.

It is obvious that many mild changes may be made in the form of construction of this invention without departing from the material principles thereof. It is not, therefore, desired to confine the invention to the exact form herein shown and described, but it is wished to include all such as properly come within the scope claimed.

Having thus described the invention, what is claimed as new is:

1. In a milking pail, the combination with a body, of supporting-arms pivotally mounted adjacent the upper edge of said body, a bail pivotally attached to said supporting-arms, and means on said bail and supporting-arms to cause the arms and bail to move in unison and in opposite directions.

2. The combination with a milk-pail, of supporting-arms hinged at the upper edge of said pail, means to hold said arms in ele-

vated position, and other means to hold said arms in dropped position.

3. The combination with a milk-pail, of supporting-arms provided with angular portions having slots therein, rivets carried by the pail and passing through said slots, a bail having ends placed to bear against the angle-portions of the supporting-arms, and means to hold said arms in a lowered position.

4. The combination with a milk pail, oppositely-disposed lugs fixed at the upper edge of said milk pail, said lugs each including a body having an opening at its lower portion adapted for the reception of a portion of a supporting-arm, said lugs each further having a bail end-receiving opening at its upper portion, a bail having ends disposed in the receiving-openings, and extremities arcuate in form and lying in planes at right-angles to the plane of the bail adjacent said lugs, supporting-arms pivotally mounted in the first-mentioned opening and having feet projecting through the openings and engaging the arcuate bail-ends, and means to retain said supporting-arms in a lowered position.

In testimony whereof I hereunto affix my signature in presence of two witnesses.

CONRAD EKVALL.
